CLAIM

The ornamental design for a device for protection against radiation, as shown and described.

DESCRIPTION

FIG. 1 is a bottom view of a device for protection against radiation showing our new design.

FIG. 2 is a top view thereof.

FIG. 3 is a perspective view of the top thereof.

FIG. 4 is an enlarged front view thereof, the rear view being a mirror image; and,

FIG. 5 is an enlarged right side view thereof, the left side view being a mirror image.
